Harold E. Smith Attorney

UNITED STATES PATENT OFFICE

HAROLD WIEDEMANN, OF SEATTLE, WASHINGTON

DISPLAY TABLET

Application filed January 3, 1929. Serial No. 330,085.

My present invention relates to improvements in display tablets or markers, which while adapted for use in various ways, are especially designed for use as memorial tablets, grave markers, &c.

The display tablet of my invention is of that type utilizing artificial stone fashioned from plastic material suitable for the purpose, together with metal characters, symbols, floral designs, insignia, ornamental features, &c., and the invention consists in certain novel combinations and arrangements with the body of the tablet or slab, of these metal characters, etc., as will hereinafter be 10 more fully set forth and claimed. Means are provided whereby the letters, or other features forming the display, are permanently secured in the tablet or slab against displacement, thus forming a durable device of this 15 character. The parts forming the invention are simple in construction, may readily and with facility be assembled to provide a comparatively inexpensive cost of production, and at the same time the tablet or slab presents a neat and artistic appearance.

Means are provided whereby the subject matter displayed on the tablet may be artificially illuminated by the use of electric lights which are invisible, or natural lighting effects may be attained, either by the use of colored glass or other transparent material, or by the reflection of natural light rays on the surface of the inscription or ornamental features of the tablet.

In the accompanying drawings I have illustrated one complete example of my invention physically embodied in a grave marker or memorial tablet, and in which the parts are combined and arranged according to the best mode I have thus far devised for the practical application of the principles of my invention, but it will be understood that the invention may be embodied in other articles.

Figure 1 is a perspective view of a memorial tablet constructed according to my invention.

Figure 2 is an enlarged detail view showing the manner of spacing, arranging and 50 fastening together the symbols, here shown

as letters, before they are embedded in the plastic material, which when hardened forms the body of the tablet.

Figure 3 is an enlarged sectional detail view, transversely of the tablet, as at line 55 3—3 of Figure 1.

Figure 4 is an end elevation of the letters as used at line 4—4 of Figure 2.

The body 1 of the tablet is preferably fashioned from artificial stone, which is fashioned in a mold from plastic material, and afterward dried and hardened to form a durable body for the tablet.

The upper face 2 for the inscription, data, ornamentation, &c., is preferably inclined, 65 and polished if desired, and the subject matter displayed as letters 3, ornamental border 4, floral design 5, and dates 6, are all flush with the face of the tablet. These enumerated features are embedded in the face 70 of the tablet and retained therein against displacement. For instance, the letters as L E E in Figure 2 are fashioned of channel, cast metal, each designated as 7, and the letters are provided with inclined faces 8 to co-act 75 with the inclined walls of grooves 9 in the face of the tablet. The letters are thus retained by a dove-tail formation in the face of the tablet, and the upper edges 10 of the letters are flush with the face of the tablet. 80 In the faces of the letters are grooves 10a extending throughout the entire area of the letters, and beneath these grooves are countersunk recesses 11, with holes or apertures 85 12 extending through the bottom walls of the letters.

The letters are assembled, arranged, and spaced in alinement for the formation of the desired subject-matter before being placed in the plastic material or in the mold to which the plastic material is later added, and to retain the letters in their predetermined relations I utilized tie bars 14. Three of the tie-bars are illustrated in Figure 2 and they are attached, as by spot-welding, or by soldering, at the backs of the letters. The tie bars also become embedded in the artificial stone and furnish additional anchoring means with the dove-tail arrangement of the letters in the face of the tablet.

In the grooves 10a of the letters are seated and cemented panels 15 of glass or other suitable material, while in the border 4, panels of glass, or other suitable material, indicated as 16, are cemented in the grooves 10 of the border. The floral design 5 and the dates 6, appearing on the face of the tablet are fashioned in like manner of grooved metal with contrasting panels inserted therein.

10 In some instances the natural light rays may be reflected from the panels in the letters and other features displayed on the face of the tablet, for the purpose of illuminating the letters and features so that they will have a 15 prominent appearance on the face of the tablet.

For artificial illumination of the features displayed I may use incandescent electric lamps as 17 that are enclosed in a lamp box 20 that is cast in the body of the tablet when the latter is fashioned in its mold, and the wires 19 from a suitable source are passed through an open plug 20 fixed in the removable bottom 21. The bottom has its edges 25 seated in a side groove 22 extending around the edges of the box, and the bottom carries a turn button 23 having a fastening head 24 within the box that frictionally engages the fastening lug 25 of the box, to retain the 30 bottom in closed position, or to release the bottom so that it may be removed to permit access to the interior of the box. In the top of the box are openings 26 through which light rays from the lamps 17 pass to illuminate 35 the transparent panels 15.

Having thus fully described my invention, what I claim as new and desire to secure by Letters Patent is:—

1. The combination with a hardened plastic 40 stone, of spaced channel-shaped letters embedded therein having edges flush with the face of the stone, tie bars connecting said letters and embedded in the stone, grooves in the side walls of the channel-shaped letters, 45 and panels of transparent material in said grooves.

2. The combination with an artificial stone 50 having a lamp box cast therein and said lamp box being covered by the stone, of channel-shaped letters cast in said stone above the lamp box, said letters having countersunk grooves open to the lamp box, lamps in the box, and transparent panels seated in said letters and closing the grooves of the letters.

55 In testimony whereof I affix my signature.
HAROLD WIEDEMANN.
